Attorney

UNITED STATES PATENT OFFICE.

IDA B. FELDMAN, OF ATLANTA, GEORGIA.

INSECT-TRAP.

1,277,301.

Specification of Letters Patent. Patented Aug. 27, 1918.

Application filed July 20, 1917. Serial No. 181,773.

To all whom it may concern:

Be it known that I, IDA B. FELDMAN, a citizen of the United States, and resident of Atlanta, in the county of Fulton and State 5 of Georgia, have invented certain new and useful Improvements in Insect-Traps, of which the following is a specification.

This invention relates to improvements in insect traps; the dominant object of the 10 invention being to provide a fly trap capable of attachment to a screen, shade, curtain or the like, and when in position thereon, will serve to attract flies thereto, the trap being transparent and subjected to light.

15 Another object of the invention is to provide novel means for supporting the trap in proper position with relation to an article, which support can be readily removed and folded if desired.

20 Among other aims and objects of the invention may be recited the provision of a device of the character mentioned with a view to compactness, and in which the number of parts are few, the construction simple, the 25 cost of production small and efficiency in operation high.

The foregoing together with additional 30 advantageous details of arrangements of parts of the preferred embodiment of my invention will be clear from the specific description hereinafter contained, when read in connection with the accompanying drawings forming part thereof, wherein said embodiment of the invention is illustrated for 35 the purpose of facilitating a full understanding of the present improvements.

In the drawings:

Figure 1 is a perspective of the improved trap as applied to a substantially dark back 40 ground such as a screen or the like; and

Fig. 2 is a vertical transverse section therethrough.

Referring now more particularly to the drawings and in connection with like reference characters which refer to the same parts in the several views, 1 designates the usual type of portable screen adapted for arrangement in windows, etc., the screen being preferably of material which will render a substantially dark background. An opening is formed preferably, concentrically of the screen, and receives therethrough the neck of a transparent receptacle 2, which receptacle is removably supported upon a bracket 50 indicated in its entirety by the numeral 3.

The bracket 3 comprises strips of metal

having their adjacent ends hinged as at 4, the upper piece being normally supported in a substantially horizontal plane by means of a spring arm 5 having one end pivoted to the said upper piece as at 6 while its remaining end is slightly bent and bifurcated as at 7 in order that the same may be arranged about a pin 8 or other projection carried upon the lower bracket piece in proximity of its bottom. To secure the bracket 3 of the screen, rivets or like fastening devices 9 are passed through the bottom portion thereof into engagement with the bottom portion of the screen frame. A spring clip 10 is arranged upon the upper bracket piece, and, obviously, embraces the sides of the transparent receptacle, the said upper bracket being preferably formed concavo-convex in order that the receptacle, which is circular 75 may be readily seated thereon.

If desired, a stopple may be supplied the transparent receptacle 2 in order that it may be closed when removing the same from engagement with the screen 1.

In operation, the transparent receptacle is placed adjacent the screen 1 and has the neck thereof passed through the opening formed in the said screen. A poison or adhesive is then placed in the receptacle and, obviously, serves as means for killing such insects as may enter the same. Due to the substantially dark background afforded by the screen 1, flies and other insects will be attracted to the transparent receptacle which is subjected to light and seeking an exit will readily crawl or move thereinto. Upon emptying the receptacle, a stopple may be placed in the neck thereof and the same then removed from engagement with the screen 95 and the supporting bracket 3 whereupon it can be emptied.

I also desire to have it understood that my improved trap may be used in connection with any article, such as a curtain, shade or the like which will afford a substantially dark background for the same in order that the transparent receptacle when passed through a suitable opening formed therein will serve as the center of light and as a consequence, attract the flies and insects thereto. Further, the bracket 3 may be formed of a single piece of metal which can be either detachably or permanently secured to an article which I so call the background 105 of the trap.

Manifestly, the construction shown is ca-

able of considerable modification and such modification as is within the scope of my claims, I consider within the spirit of my invention.

5 I claim.

1. The combination with an apertured substantially dark support, of an angular bracket secured to the same and having one portion alining with the aperture, a transparent receptacle supported thereon and extending through said aperture, and resilient gripping means on the alining portion of the bracket to secure the receptacle in position.

10 2. The combination with an apertured substantially dark support, of an angular bracket having a rigid portion secured to the support and the other portion movable in and out of axial alinement with the aperture, means to support the movable portion in 15 said alinement, a transparent receptacle sup-

ported on said movable portion and adapted to extend through the aperture, and resilient gripping means on said last mentioned portion to secure the receptacle thereon.

25 3. The combination with an apertured substantially dark support, of a bracket being formed of a pair of hingedly connected strips, one strip being secured to the support, means for removably supporting the other strip in axial alinement with the apertures through the support, a transparent receptacle on said last mentioned strip adapted to extend through the aperture, and resilient gripping means thereon for engagement with the receptacle.

30 In testimony whereof, I affix my signature hereto.

IDA B. FELDMAN.

Copies of this patent may be obtained for five cents each, by addressing the "Commissioner of Patents, Washington, D. C."
